UNITED STATES PATENT OFFICE

2,035,969

ROTARY HOOK FOR SEWING MACHINES

Harold J. Le Vesconte, Western Springs, Ill., assignor to Union Special Machine Company, Chicago, Ill., a corporation of Illinois

Application November 30, 1934, Serial No. 755,494

7 Claims. (Cl. 112—256)

The present invention relates to new and useful improvements in a rotary hook for a lock stitch sewing machine and more particularly to improved means for furnishing lubricant to the interengaging parts between the rotary hook and the stationary bobbin casing.

An object of the invention is to provide a rotary hook wherein means are provided for directing lubricant from a source of supply adjacent the axis thereof to the connecting portions between adjacent spokes and thence to the interengaging parts between the rotary hook and the stationary bobbin casing.

A further object of the invention is to provide a rotary hook wherein means are provided for directing lubricant from a source of supply at the axis thereof to the connecting portions between adjacent spokes and wherein means are provided for forming channels along said connecting portions to the inner face of the hook rim whereby lubricant is caused to flow by centrifugal force to the interengaging parts between the rotary hook and the stationary bobbin casing.

The above and other objects of the invention will in part be obvious and will be hereinafter more fully pointed out.

In the accompanying drawings:

Figure 1 is a side elevation, in section, showing the assembled rotary hook, the actuating shaft therefor, and the bushing in which the shaft rotates.

Figure 2 is a front elevation of the hook with the bobbin casing removed.

Figure 3 is a rear elevation of a portion of the hook.

Figure 4 is a perspective view showing one of the channel forming members.

Figure 5 is a sectional view taken along the line 5—5 of Fig. 2.

Figure 6 is a side elevation, in section, similar to Fig. 1, but showing a modified form of the invention.

Figure 7 is a front elevation of the hook, shown in Fig. 6, with the bobbin casing removed.

Figure 8 is a sectional view taken along the line 8—8 of Fig. 7.

The invention relates generally to means for furnishing lubricant to the interengaging parts between the rotary hook and the stationary bobbin casing. The rotary hook is provided with a rim portion, a hub and spokes connecting the hub and rim portions. The hub of the rotary hook is fixed to the end of a rotating shaft in position to leave a recess at the end thereof and the bobbin casing is mounted within and supported by

the hook. The bobbin casing is provided with a circumferential rib which fits within and moves in a groove or raceway in the hook rim and thus prevents relative lateral movement between the hook and the casing. A portion of the bobbin casing engages a fixed part of the sewing machine in order to prevent rotation thereof within the hook. The actuating shaft for the hook is supported in a bushing which is mounted in a bearing bracket depending from the work support 10 of the sewing machine. The bushing is provided with an opening through which oil may flow from a source of supply to a central bore in the actuating shaft. The bore communicates with the recess in the hub. The hub is provided with radial 15 ports leading from the recess therein to the web portions connecting adjacent spokes. The web portions may be provided, in one instance, with grooves leading to the inclined edge of the rim portion or with removable channel members 20 which form oil channels leading to the inclined edge of the rim. Oil admitted to the recess in the hub through the shaft will be caused by centrifugal force to flow through the ports to the web or connecting portions between adjacent 25 spokes from which point the oil will follow the inclined inner face of the hook rim to the interengaging parts between the rotary hook and the stationary bobbin casing.

Referring more in detail to the accompanying drawings, and particularly at this time to Figs. 1—5 inclusive, the invention is shown as applied to a sewing machine having a work support 10 which is provided with a depending bearing bracket 11 within which is mounted a bushing 12. 35 The actuating shaft 13 is mounted within the bushing 12 and the rotary hook 14 is secured to the end of the shaft by a screw 15 or the like, passing through the hub 16. The particular manner in which the actuating shaft for the rotary hook is driven forms no part of the present invention and it is to be clearly understood that it may be driven in any suitable manner. For purposes of illustration, however, the actuating shaft 13 may be driven by suitable intermeshing 40 gears, as shown in the copending application of George Sauer, Serial No. 688,512, filed September 7, 1933, and described in detail in the copending application of Norman V. Christensen et al., Serial No. 670,186, filed May 9, 1933. The shaft 50 13 may also be driven in the manner shown and described in the copending applications of George Sauer, Serial Nos. 716,415 and 716,416, filed March 19, 1934.

The rotary hook is of the usual cup-shaped con- 55

struction having a rim portion 17, a hub 16 and spaced radial spokes 18 connecting the hub and rim portion. The bobbin casing 19 is provided with a circumferential rib 20 which fits within a groove or raceway 21 in the rim portion 17 of the rotary hook. The rib 20 and raceway 21 form interengaging parts between the rotary hook and the stationary bobbin casing to prevent lateral movement of the casing relative to the rotary hook. The bobbin casing is also cup-shaped to receive a bobbin 22 which is held by a cover or carrier 23. The bobbin casing is provided with a projecting portion 24 which engages a fixed part of the sewing machine and prevents the rotation thereof within the rotary hook. One side wall of the rotary hook is cut away to provide a hook which is adapted to enter the needle thread loop and carry the same about the bobbin casing 19. The rotary hook operates in the usual manner and further description thereof is not considered necessary.

The hub 16 of the rotary hook is secured on the end of the shaft 13 in position to leave a recess 26 therein which is closed by a plate 27 in order to provide a closed recess to prevent lubricant from passing directly to the inner face of the hook. The webs or connecting portions 28 between adjacent spokes 18 are provided with radial ports 29 which communicate with the recess 26 in the hub 16. As shown in Figs. 1-5, U-shaped channel forming members 30 having depending sides 30a are fitted over the connecting portions 28 between adjacent spokes to provide suitable lubricant conducting channels leading up the edges of adjacent spokes. The extreme edges of the spokes are inclined inwardly of the rotary hook, as at 31, and merge into the inclined inner face 32 of the rim portion 17.

The depending bearing bracket 11 is provided with an oil hole 33 which communicates with an opening 34 in the bushing 12. The shaft 13 is provided with an axial recess 35 which opens into the recess 26. A radial opening 36' in the shaft 13 permits oil to pass from the oil hole 33 through the opening 34 in the bushing to the axial recess 35 in the shaft from which it passes into the recess 26 in the hub 16 of the rotary hook. As the hook rotates, oil will be caused to flow by centrifugal force through the ports 29 to the channels formed by the channel members 30 along the connecting portions 28 between adjacent spokes 18. Oil will flow along the connecting portions to the inclined edges 31 of the spokes and from there the oil will be caused to flow along the inner face 32 of the rim 17 to the interengaging parts between the rotary hook and the stationary bobbin casing, that is, to the interfitting rib 20 and raceway 21.

In Figs. 6-8 inclusive, a slightly modified form of the invention is shown. The manner in which the rotary hook, the bobbin 22 and bobbin casing 19 are assembled is the same as described in connection with Figs. 1-5. Similarly, the oil reaches the recess 26 in the hub 16 of the rotary hook from the recess 35 in the shaft 13 in the manner shown in Figs. 1-5, so that further description thereof at this time is not necessary. The webs or connecting portions 28a between adjacent spokes 18a, in this form of the invention, are provided with ports 29 which communicate with the recess 26 in the hub 16. From the outer end of each port 29, a groove 36 extends along each connecting portion 28a and spoke 18a in a direction opposite to the direction of rotation of the hook, as indicated by the arrows A in Fig. 7.

The grooves 36 lead to an inclined edge 37 on each spoke which merges into the inclined inner face 32 of the rim 17. Oil reaching the recess 26 from the oil hole 33 and recess 35 will be caused to flow by centrifugal force through the ports 29 to the grooves 36. As the rotary hook rotates in the direction indicated by the arrows, the oil will be caused to pass along the grooves 36 in the opposite direction and will be directed by the inclined edges 37 along the inner face 32 of the rim 17 to the interengaging parts between the rotary hook and the stationary bobbin casing to lubricate the rib 20 and raceway 21.

While a plurality of ports and oil channels along the spokes have been illustrated, it is to be understood that only one may be employed, if desired. The present invention provides a highly efficient means for lubricating the interengaging parts between the rotary hook and the stationary bobbin casing, and it is to be clearly understood that minor changes in the details of construction and arrangement of parts may be made without departing from the scope of the invention as set forth in the appended claims.

Having thus described the invention, what I claim as new and desire to secure by Letters Patent, is:

1. In a sewing machine, the combination of a rotary hook having a hub, a rim portion and connected spokes joining said hub and rim portion, a stationary bobbin casing supported within said rotary hook, said casing and said rim portion having interengaging parts to prevent relative lateral movement between said hook and said casing, and means for furnishing lubricant from a supply at the axis of said hub to said interengaging parts and including lubricant conducting means on the edge of one of the connecting portions between adjacent spokes.

2. In a sewing machine, the combination of a rotary hook having a hub, a rim portion and connected spokes joining said hub and rim portion, a stationary bobbin casing supported within said rotary hook, said casing and said rim portion having interengaging parts to prevent relative lateral movement between said hook and said casing, and means for furnishing lubricant from a supply at the axis of said hub to said interengaging parts and including lubricant conducting passages formed on the connecting portions between adjacent spokes.

3. In a sewing machine, the combination of a rotary hook having a hub, a rim portion and spokes connecting said hub and rim portion, said spokes being joined adjacent said hub by web portions, of a stationary bobbin casing supported within said hook, said rim portion and casing having interengaging parts to prevent relative lateral movement between said hook and said casing, means for forming lubricant conducting passages along the edges of said web portions to the inner face of said rim portion, and means for furnishing lubricant from a supply at the axis of said hook to said web portions whereby lubricant will be caused to flow to said interengaging parts.

4. In a sewing machine, the combination of a rotary hook having a hub, a rim portion and spokes connecting said hub and rim portion, said spokes being joined together adjacent said hub by web portions, of a stationary bobbin casing supported within said hook, said casing and said rim portion having interengaging parts to prevent relative lateral movement between said casing and said hook, and means for fur-

nishing lubricant from a supply at the axis of said hub to said interengaging parts and including a removable member secured to a web portion and forming therebetween a channel 5 through which lubricant is caused to flow.

5. In a sewing machine, the combination of a rotary hook having a hub, a rim portion and spokes connecting said hub and rim portion, said spokes being joined adjacent said hub by web 10 portions, of a stationary bobbin casing supported in said hook, said casing and said rim portion having interengaging parts to prevent relative lateral movement between said hook and said casing, said hub having a lubricant containing 15 recess at the axis thereof, ports leading from said recess to said web portions and through which lubricant is caused to flow by centrifugal force, and means for directing lubricant to said interengaging parts and including grooves in 20 said web portions extending from said ports in a direction opposite to the direction of rotation of said hook whereby lubricant is caused to flow to the inner face of said rim and to said interengaging parts.

25. 6. In a sewing machine, the combination of a rotary hook having a hub, a rim portion and spokes connecting said hub and rim portion, said spokes being joined adjacent said hub by web portions, of a stationary bobbin casing supported 30 within said hook, said casing and rim portion having interengaging parts to prevent relative lateral movement between said hook and said casing, an actuating shaft on which said hub is secured in position to leave a lubricant containing recess, means for furnishing lubricant to said recess, ports passing radially 35 to said recess, 35

through said web portions and communicating with said recess, whereby lubricant is caused to flow therethrough by centrifugal force, and a channel member tightly fitting over the edge of each of said web portions and extending along 5 the edges of adjacent spokes and forming therebetween lubricant conducting passages, said spokes having inclined edges merging into the inner face of said rim portion whereby lubricant is caused to flow through said passages to said 10 interengaging parts by centrifugal force.

7. In a sewing machine, the combination of a rotary hook having a hub, a rim portion and spokes connecting said hub and rim portion, said spokes being joined adjacent said hub by web 15 portions, of a stationary bobbin casing supported within said hook, said casing and rim portion having interengaging parts to prevent relative lateral movement between said hook and said casing, an actuating shaft on which said 20 hub is secured in position to leave a lubricant containing recess, means for furnishing lubricant to said recess, ports passing radially through said web portions and communicating with said recess, whereby lubricant is caused to 25 flow therethrough by centrifugal force, and a groove formed in the edge of each of said web portions and extending from the adjacent port along the edge of one spoke in a direction opposite to the direction of rotation of said hook, 30 each of said spokes having an inclined edge at the end of said groove merging into the inner face of said rim portion whereby lubricant is caused to flow by centrifugal force along said 35 grooves to said interengaging parts. 35

HAROLD J. LE VESCONTE.
